Primary Examiner — Kelley Donnelly(74) Attorney, Agent, or Firm — Michael N. Cohen; Cohen IP Law Group P.C.(57) CLAIM

I claim the ornamental design for the bottle, as shown and described.

DESCRIPTION

FIG. 1 is a front perspective view of a candle wall;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view showing environment.

The broken lines in FIGS. 1 through 8 are for the purpose of illustrating the environment of the article only and form no part of the claimed design.
